UNITED STATES PATENT OFFICE.

JOHN J. GILBERT, OF PORT WASHINGTON, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed November 14, 1921. Serial No. 514,845.

To all whom it may concern:

Be it known that I, JOHN J. GILBERT, a citizen of the United States, residing at Port Washington, in the county of Nassau, 5 State of New York, have invented certain new and useful Improvements in Signaling Systems, of which the following is a full, clear, concise, and exact description.

This invention relates to telegraph systems and more particularly to submarine cable telegraph systems.

In duplex telegraph systems where current impulses are transmitted over a single conductor in opposite directions simultaneously, 15 it is impossible to secure and maintain a perfect balance between the real and artificial lines. Consequently considerable difficulty is experienced owing to disturbances caused by the initial surge of current due to a change 20 of polarity applied to the signaling conductor, which tends to effect distortion of the incoming signals, and which may have a harmful effect upon the subsequent action of the apparatus used in correcting and amplifying 25 the received signals.

The principal object of this invention is the minimizing of the effects of such disturbances.

In carrying out this object there is preferably provided means associated with the signaling system utilizing duplex equipment whereby the receiving instrument may be alternately operatively connected with, and disconnected from, the real and artificial 35 lines.

Other objects of the invention will hereinafter appear.

In the drawing, Fig. 1 is a diagrammatic illustration of a duplex cable system embodying the invention; Fig. 2 shows a curve useful in describing the operation thereof; and Fig. 3 shows a special application of the invention to high speed signaling systems employing transmitting and receiving distributors.

Referring first to Fig. 2, a typical case of unbalance is illustrated, the curve A, B, C, D representing the current in the receiving instrument at one end of the line due to voltage applied to the duplex network by the transmitter at the same end of the line during the interval AE. The portion A, B, C usually occupies only a small fraction of this interval, but on account of its large amplitude, it may interfere seriously with the in-

coming signals. The remainder of the unbalance C, D is of comparatively small amplitude and its effect on the received signal is not as serious. Referring now to Fig. 1, there is shown the usual Wheatstone bridge arrangement in which cable 6 constitutes one arm of the bridge. Another arm of the bridge is represented by an artificial balancing network 7 comprising suitable resistances and condensers connected to ground in the usual manner, the usual condensers 8 and 9 being provided in the two other arms of the bridge. In the "bridge" is an amplifier or shaping and correcting network 10 connected to the windings of a polarized relay 11 which, in turn, controls a local circuit including a source of current 12 and a recording instrument or sounder 13. The transmitter may include a rotatable drum 14, a perforated tape 15 and associated brushes 16, 17 and 18. Associated with the transmitting drum members are neutral relays 19 and 20 and energizing batteries 21 and 22 for controlling a battery 23, in the manner well understood in the art, to impress currents of either polarity upon the line. It is common practice in systems of duplex and multiplex telegraphy to connect the amplifying network 10 and receiving relay 11 directly across the arms 6 and 7 of the bridge, the accuracy of the systems depending upon the artificial network 7 which should have exactly the same electrical resistance and capacity as the real line 6. In accordance with the present invention, however, only one terminal of the receiving apparatus is permanently connected in the bridge, as at 24, the other end being connected in such a way that it may alternately be connected to and disconnected from the bridge. This is accomplished in the present case by means of a brush 25 in circuit with the artificial network 7 and a brush 26 in circuit with the amplifying network 10, these brushes being adapted for alternate engagement with conducting segments 27 and the non-conducting surface of the distributor frame 28. When the brushes 25 and 26 rest upon conducting segments 27, as shown in the drawing, the receiving relay 11 is connected through the amplifying network 10 to the artificial balancing network 7, and when these brushes rest on the non-conducting surface 28, the receiving apparatus is insulated from the duplex network. The dis-

tributor frame 28 is preferably positioned on the rotatable transmitting drum 14. The uniform conducting segments 27 are shorter than the tape perforations in the transmitting tape 15 and are so oriented with respect to the perforations that the transmitting brush 17 or 18 will enter upon the conducting surface of the drum 14 in advance of the entrance of the brushes 25 and 26 upon a segment 27. Thus, as the drum 14 is rotated past the stationary brushes, the receiving instrument 11 will be insulated from the network 7 at the beginning of each impulse during the time AC, at which time the disturbance due to unbalance would be received. At all other times, however, the brushes 25 and 26 are resting on a segment 27 and the receiving relay 11 is connected in operative relation with the duplex network and signals from the distant end may be received.

Referring now to the modification shown in Fig. 3, the same Wheatstone bridge arrangement shown in Fig. 1 is employed, but in place of the tape transmitter and receiving sounder, a synchronous distributor is employed at each end of the line. One ring of segments 29 on the distributor is used for transmitting signals, the segments in this ring being of uniform length. A second ring of segments 30 is provided in place of the frame 28, described above, by means of which the receiving relay 11 is alternately insulated from and connected to the balancing network 7. A third ring of receiving segments 31 is also provided, each segment being electrically connected with an electromagnet of the printer 32. The tape transmitter 33, adapted for impressing currents of either polarity from a suitable source upon the line, is connected with the transmitting segments 29 in the usual manner. The brush 34 is associated with the transmitting segments 29, the brush 35 with segments 30, and the brush 36 with the receiving segments 31, these brushes being adapted for synchronous movement in the manner well understood in the art. It will be evident that of the synchronously moving brushes 34, 35, and 36, the brush 34 will enter upon a transmitting segment 29 before the brush 35 enters upon a segment 30; or in other words, the receiving relay 11 will be disconnected from operative relation with the duplex network during the very first part of each signaling impulse, or at the time when due to unbalance the greatest disturbance would ordinarily be received. At all other times, however, the receiving instrument is connected to the electrical network and signals from the distant end may be received. In order that any desired portions of the received signal will arrive at a time when the receiving instrument

is connected, it would simply be necessary

for the receiving or transmitting rings on the distant distributor to be oriented properly with respect to the segments of the transmitting or receiving distributor at the near end. By mutual arrangement both receiving instruments may be freed from the effect of unbalance.

What is claimed is:

1. The method of eliminating disturbances due to duplex unbalance in cable telegraphy which comprises automatically disconnecting the receiving apparatus from operative relation with the duplex network during the time when the major portion of the disturbance is received, and at all other times automatically maintaining the receiving instrument in operative relation with the duplex network.

2. The method of eliminating disturbances due to duplex unbalance in cable telegraphy which comprises removing the receiving apparatus from operative relationship with the duplex network at or slightly before the instant that large unbalance current is produced by the application of potential to the artificial line by the transmitter, maintaining the receiving apparatus out of operative relationship with the duplex network as long as said large unbalance current is flowing, and at all other times during the transmission of signals maintaining the receiving instrument operatively connected with the said network.

3. The combination with a telegraph line of a duplex network at each terminal comprising an artificial line, means at each terminal for applying signaling potential to said line, receiving apparatus at each terminal, means for stopping reception at each terminal during a portion at least of the time sending from that terminal occurs whereby the effect of imperfect duplex bridge balance is decreased, and means for maintaining synchronism between said stopping means at the two terminals.

4. In a telegraph system, a main line, an artificial line, means for applying signaling potential to said main and artificial lines, receiving apparatus, and means for automatically removing said receiving apparatus from operative relationship with said artificial line at or slightly before the instant that large unbalance current is produced by the application of said signaling potential to the artificial line and for maintaining said receiving apparatus in operative relationship with said artificial line at all other times during the transmission of signals.

5. In a telegraph system, a main line, an artificial line, a bridge connecting the main and artificial lines, a receiving instrument in said bridge, a transmitter for impressing signaling potential impulses of equal length, and means for alternately and

regularly disconnecting said receiving instrument from, and connecting it to, said bridge, each period of disconnection beginning at or slightly before the instant of application to said bridge of each signaling potential impulse.

6. In a telegraph system, a main line, an artificial line, a bridge connecting the main and artificial lines, a receiving instrument in said bridge, a distributor for impressing signaling potentials upon said bridge and for alternately and operatively inserting said receiving instrument in and removing it from said bridge synchronously with the impression of signaling potentials upon said bridge.

7. In a telegraph system, a main line, an

artificial line at each terminal, a bridge at each terminal connecting the main and artificial lines, a receiving instrument in each of said bridges, a rotary distributor at each terminal for impressing signaling impulses of equal length upon said main and said artificial lines and for alternately connecting said receiving instrument to, and removing it from, said bridge synchronously with the impression of signaling impulses, and means for maintaining said distributors in synchronism.

In witness whereof, I hereunto subscribe my name this 10th day of November A. D., 1921.

JOHN J. GILBERT.
